Emery LLP

CLAIM

The ornamental design for a handle for kitchen knives, as
shown and described.

DESCRIPTION

1. Handle for kitchen knives
2. Handle for kitchen knives
3. Handle for kitchen knives
4. Handle for kitchen knives
- 1.1: Top
- 1.2: Bottom
- 1.3: Back
- 1.4: Front
- 1.5: Left
- 1.6: Right
- 1.7: Perspective
- 2.1: Top
- 2.2: Bottom
- 2.3: Back
- 2.4: Front
- 2.5: Left
- 2.6: Right
- 2.7: Perspective
- 3.1: Top
- 3.2: Bottom
- 3.3: Back
- 3.4: Front
- 3.5: Left
- 3.6: Right
- 3.7: Perspective
- 4: Surface Pattern

1 Claim, 22 Drawing Sheets
